GYRATORY CRUSHER WITH DISPLACE-
ABLE SHAFT FOR RELIEVING EXCES-
SIVE CRUSHING STRAINS

Samuel W. Traylor, Jr., Allentown, Pa.

Application August 22, 1946, Serial No. 692,236

12 Claims. (Cl. 241—211)

1

This invention relates to gyratory crushers and in particular to means for relieving excessive strains arising during operation of such crushers due to the engagement of uncrushable fragments between the head and concave. More particularly, the invention is concerned with gyratory crushers wherein a top bearing is provided for the gyratory shaft and the main object of this invention is to provide a turnable member in association with the top bearing, which member is normally yieldably maintained against turning but can turn under excessive crushing pressure to permit translational displacement of the shaft and head for relief of the strain. In accordance with one embodiment of the invention, the turning of the said member permits downward translational movement, or lowering, of the shaft and head, and in accordance with another embodiment the turning thereof permits lateral translational displacement of the shaft and similar movement of the head. In both embodiments a cam and follower, or an incline-and-follower connection are provided between the turnable member and a non-rotatable part, so that the member is turned against the force of yieldable spring means by a camming action upon translational displacement of the shaft. Examples of both embodiments are shown in the accompanying drawing, in which:

Figure 1 is a plan view, partly in section substantially on line 1—1 of Figure 2, of a crusher providing vertical relief.

Figure 2 is a section substantially on line 2—2 of Figure 1.

Figure 3 is a section substantially on line 3—3 of Figure 2.

Figure 4 is an elevation, partly in section substantially on line 4—4 of Figure 5, of a modified form of crusher providing for horizontal relief, and

Figure 5 is a section substantially on line 5—5 of Figure 4.

Referring to Figures 1 to 3, reference numeral 10 designates the upper section of a crusher frame carrying a concave 11. Section 10 also includes a spider having arms 12, 13 and 14 supporting a hub 15 above the concave, the arms being directed substantially tangentially to the hub.

The hub has a vertical bore 16 coaxial with the concave, the bore being somewhat upwardly enlarged at 17 and terminating downwardly at an annular shoulder 18 below which are formed vertical grooves 19 closed at the top by shoulder portions 18'. Journalled in the bore 16 is a ring member or nut 20 provided with steep threads 21, the threads having, for example, a 45 degree pitch. The threads 21 engage the complementary threads of sleeve 22 which, at its lower end, has a connection with the hub, constituted by

outwardly projecting lugs 23 slidable in grooves 19 but preventing rotation of the sleeve relative to the hub. The sleeve 22 thus constitutes a part restrained against rotation in the hub 15. Received in the sleeve 22 with clearance for gyratory and rotational movement is the upper end of an upright gyratory shaft 24 which is threaded and has engaged therewith a suspension nut 25, said nut and sleeve having spherical contacting surfaces with a center on the neutral point 26 of the shaft. The lower end of shaft 24 is received with freedom for vertical adjustment in an eccentric adapted to be driven in the usual manner, the vertical adjustment of the shaft being accomplished by adjusting nut 25. Within the concave, shaft 24 carries a head 27 which includes a mantle 28 and, as here shown, a floating ring 29 is disposed in the crushing space, such ring forming no part in the present invention and being covered in my co-pending application Serial No. 643,033, filed January 24, 1946.

Secured to the bottom of the hub is a cap 30 having a central opening receiving shaft 24 with the necessary clearance, the opening being de-

fined by a flange portion 31 whose top surface is spherical on the center 26. Bearing against the said top surface is a spherical ring 32 which closely slidably embraces the shaft, the spherical top of ring 32 being engaged by the spherical bottom surface of a further ring 33 which is urged downwardly by a spring 34 engaged between it and sleeve 22. There is thus provided an effective seal for the bottom of the lubricant chamber 35.

Arm 12 has an outward extension 36 providing a spring pocket having an opening or passage 37 substantially tangential to nut 20. Disposed in the spring pocket is a strong compression spring 38 whose outer end is engaged by an abutment 39 to which is secured one end of a cable 40 whose other end portion is wound on the nut and received in a circumferentially extending groove 41 of the latter, the extremity of the cable being zinned in a conical recess 42 which leads from a notch 43. The other arms of the spider include similar spring pockets 44 and 45 housing tensioning springs for cables 46 and 47, Figure 2, which are wound on and anchored to the nut in the same manner as cable 40, the cables being at different heights so as not to interfere. The spring pockets are equi-angularly arranged around the hub and the cables are equi-angularly anchored to the nut and the strength of the springs being equal, a substantially balanced torque is exerted on nut 20 to normally hold the same at one limit of its turning movement, in which the nut normally holds the sleeve in an upper limit position in which the lugs 23 engage the top walls 18' of grooves 19 to yieldingly maintain the shaft and crushing head in

the normal position determined by nut 25. However, if an uncrushable fragment enters the crushing chamber and is too large to escape thererrom so that an abnormal strain is exerted on the head, the latter will lower by reason of the downward force component as permitted by the downward threading of sleeve 22 which turns the ring member or nut 20 toward its other limit of movement, against the action of the springs. Thus, abnormal downward forces displace the head and shaft translationally in a downward direction, while rotating the nut against the force of the springs. When the fragment has been passed or removed, the springs will rotate the nut to return the sleeve 22 and therewith the shaft to normal operating relation.

The interengaged threads of the ring member or nut 20 and the non-rotatable sleeve 22 are illustrative of one type of incline-and-follower connection between the ring member and a part restrained against rotation in the hub.

In Figures 4 and 5 the frame 50 is equipped with a concave 51 and supports a spider which includes arms 52, 53 and 54 supporting a hub 55 having a vertical bore 56 concentric with the concave. Set in the wall of the bore are axially extending equidistantly spaced identical abutments 57, 58 and 59 which have inclined or wedge faces directed clockwise, Figure 4. Each abutment constitutes a part restrained against rotation in the hub 55. A cap 60 secured to the bottom of the hub provides an annular shoulder which supports a ring member 61, the latter having axially extending equidistantly spaced identical abutments 62, 63 and 64, respectively engageable as followers with the wedge surfaces of members 57, 58 and 59. Just as in the first embodiment, spring tensioned cables 65, 66 and 67 are wound on the ring member and are anchored thereto so that a substantially balanced force is exerted on the latter to engage the abutments with each other at one limit of turning movement of the ring member and thereby center the same on the axis of the concave. Member 61 is provided with a bottom ledge 68 which supports the lower member 69 of a ball socket which receives a ball 70, the upper member 71 of the socket being held in place by a threaded ring 72. The ball 70 has a diametrical bore slidingly receiving the upper end of an upright gyratory shaft 73 which carries a head 74. The lower end of the shaft is received in an eccentric in such a manner as to permit universal tilting of the shaft from its axis, the eccentric providing a bottom support for the shaft in well known manner. An oil seal, like that shown in Figure 2, is provided between the hub and the shaft.

When an uncrushable fragment is engaged between the head and concave, the abutment member 62, 63 or 64 which is opposite the point of engagement will be driven down the incline of its associated abutment member 57, 58 or 59 with consequent turn of the member 61 toward its other limit of movement against the action of the springs, so that member 61 and the shaft 73 are translationally displaced and take an eccentric position in the hub bore, thus permitting tilting of the shaft under the lateral force component to relieve the strain. When the emergency has passed, the spring action will automatically recenter member 61 for normal operation.

It will be understood that, in the second form of the invention, illustrated in Figures 4 and 5, the gyratory shaft does not move downwardly to increase the space between the crusher head and

the concave, to permit the passage of a non-crushable object, as is the case in connection with the form shown in Figures 1, 2, and 3, but, instead, the upper end of the shaft is displaced laterally for this purpose. Excessive strains imparted to the head and the shaft cause the abutments 62, 63, and 64 to move along the adjoining wedge surfaces, by relative rotation of the ring 61, thereby permitting the gyratory shaft to assume an eccentric position in the hub 55 and increasing the space in the crushing zone adjacent the non-crushable objects.

The interengaged wedge-shaped abutments 57-59 and the followers 62-64 are illustrative of another type of incline-and-follower connection between the ring member and a part restrained against rotation in the hub.

While I have shown representative embodiments of the invention, it is to be understood that other changes in the form and arrangement of the parts are possible without departure from the invention as defined in the following claims.

I claim:

1. A crusher comprising a frame and a concave supported thereby on an upright axis, an upright gyratory shaft and a head carried thereby for cooperation with said concave, a spider supported by the frame and including a central hub having a bore into which the upper end of said shaft extends, a ring member mounted for limited turning movement in the hub, surrounding the shaft and in which the shaft is rotatable, an incline-and-follower connection between the ring member and a part restrained against rotation in the hub, said connection holding the shaft in normal crushing position when the ring member is at one limit of its turning movement, said ring member being turnable toward its other limit of movement by forces transmitted through said connection as a result of and to permit, translational displacement of the shaft to relieve undue crushing strains on said head, and spring means operatively connected to said ring member normally maintaining the same at the first mentioned limit of turning movement and restraining the same against turning toward the other limit.

2. A crusher in accordance with claim 1 in which said spring means are operatively connected to the ring member by a cable connected at one end to the spring means and having its other end portion wound on the ring member and anchored thereto and in which the spring means tensions the cable.

3. A crusher in accordance with claim 1 in which the spring means are operatively connected to the ring member by a plurality of cables having end portions wound on the ring member and anchored thereto, in which the spring means are secured to the other ends of the cables respectively to tension the same, and in which the cables and spring means exert substantially balanced resistance against turning of the ring.

4. A crusher in accordance with claim 1 in which the spider is provided with a spring socket having an opening directed tangentially toward the ring member, in which a spring is disposed in the pocket and in which a cable has an end portion wound on the ring member and its other end extending through said opening into said pocket and connected to said spring, whereby the cable is tensioned to yieldingly resist turning of the ring member.

5. A crusher in accordance with claim 4 in which a plurality of spring pockets are formed

in the spider, in which each pocket contains a spring and in which a corresponding number of cables are wound on and anchored to the ring, with their other ends led through the openings into the pockets and connected to the springs therein, to yieldingly resist turning of the ring, the arrangement of the pockets, springs, and cables being such that substantially balanced resistances are exerted against such turning.

6. A crusher comprising a frame and a concave supported thereby on an upright axis, an upright gyratory shaft and a head carried thereby for cooperation with said concave, a spider supported by the frame and including a central hub having a bore into which the upper end of said shaft extends, a nut element supported in the hub in surrounding relation to said shaft end, a sleeve element interposed between said nut element and shaft and supporting the latter, said elements having a steep, vertical incline-and-follower interengagement and one thereof being stationary and the other being rotatable relative thereto, and spring means normally yieldingly restraining the rotatable element against rotation but permitting rotation thereof to enable the sleeve element and therewith the shaft to lower upon the occurrence of abnormal downward pressure on said head.

7. Structure according to claim 6 wherein said spring means is constituted by a plurality of springs arranged to act on said rotatable element with substantially balanced effect.

8. A crusher comprising a frame and a concave supported thereby on an upright axis, an upright gyratory shaft and a head carried thereby for cooperation with said concave, a spider supported by the frame and including a central hub having a bore into which the upper end of said shaft extends, a nut journaled in said hub in surrounding relation to said shaft end, a sleeve interposed between said nut and shaft and supporting the latter, a connection between the sleeve and hub maintaining said sleeve against rotation, said nut and sleeve having steep threaded interengagement, and spring means normally yieldingly restraining said nut against rotation but permitting rotation thereof to enable the sleeve and therewith the shaft to lower upon the occurrence of abnormal downward pressure on said head.

9. A crusher comprising a frame and a concave supported thereby on an upright axis, an upright gyratory shaft and a head carried thereby for cooperation with said concave, a spider supported by the frame and including a central hub having a bore into which the upper end of said shaft extends, a nut journaled in said hub in surrounding relation to said shaft end, a sleeve interposed between said nut and shaft and supporting the latter, a connection between the sleeve and hub maintaining said sleeve against rotation, said nut and sleeve having steep threaded interengagement, and a plurality of cables having end portions wound on said nut and anchored thereto, and spring means secured to the other ends of said cables respectively and tensioning the same whereby to normally yieldingly resist rotation of the nut but to permit rotation thereof to enable the sleeve and therewith the shaft to lower upon the occurrence of abnormal downward pressure on the head, said cables and spring means being arranged to act on said nut with substantially balanced effect.

10. A crusher comprising a frame and a concave supported thereby on an upright axis, an upright gyratory shaft and a head carried thereby for cooperation with said concave, a spider supported by the frame and including a central hub having a bore into which the upper end of said shaft extends, a ring supported in said bore and providing a bearing in which said shaft end is universally tiltable, said ring being universally transversely shiftable in said bore, a plurality of symmetrically disposed cooperating wedge-and-follower abutments projecting inwardly from the hub bore and outwardly from said ring respectively, the wedge abutments having circumferentially faced wedge faces and the cooperating abutments being engageable with said faces upon turning of the ring in one direction to center the ring in said bore, and spring means urging the ring in said direction to engage said abutments, the ring abutments being slideable on the hub abutments with turning effect on the ring against the force of said spring means to permit said ring and shaft end to move laterally to relieve excessive lateral strains on said head.
- 15 11. Structure according to claim 10 wherein said spring means is constituted by a plurality of springs arranged to act on said ring with substantially balanced effect.
- 20 12. A crusher comprising a frame and a concave supported thereby on an upright axis, an upright gyratory shaft and a head carried thereby for cooperation with said concave, a spider supported by the frame and including a central hub having a bore into which the upper end of said shaft extends, a ring supported in said bore and providing a bearing in which said shaft end is universally tiltable, said ring being universally transversely shiftable in said bore, a plurality of symmetrically disposed cooperating wedge-and-follower abutments projecting inwardly from the hub bore and outwardly from said ring respectively, a plurality of cables having end portions wound on said ring and anchored thereto, and spring means secured to the other ends of said cables respectively and tensioning the same whereby to urge the ring in said direction to engage said abutments, the ring abutments being slideable on the hub abutments with turning effect on the ring against the force of said spring means to permit said ring and shaft end to move laterally to relieve excessive lateral strains on said head, said cables and spring means being arranged to act on said nut with substantially balanced effect.
